Evans-Aristocrat Industries, Inc., Elizabeth, N.J.,
a corporation of New Jersey

Filed June 30, 1967, Ser. No. 7,661

Term of patent 14 years

(Cl. D52—1)

FIG. 1

FIG. 2

FIG. 3

FIG. 4

FIG. 1 is a perspective view of a tape measure showing my new design;

FIG. 2 is a rear view thereof;

FIG. 3 is an end view thereof as seen from the right of FIG. 1; and

FIG. 4 is a bottom view thereof.

The broken lines seen along the periphery of the casing in FIG. 2 are intended to indicate a continuity of ribs as viewed in the other drawing figures. The essential features of the design reside in the solid line portions of the drawing.

I claim:

The ornamental design for a tape measure or similar article, substantially as shown and described.
